UNITED STATES PATENT OFFICE.

GAÉTAN M. CORELL, OF NEW YORK, N. Y.

AUTOMATIC INSULATOR.

No. 822,043.

Specification of Letters Patent.

Patented May 29, 1906.

Application filed December 21, 1904, Serial No. 237,805

To all whom it may concern:

Be it known that I, GAÉTAN M. CORELL, a citizen of France, and a resident of the city of New York, borough of Manhattan, in the county and State of New York, have invented a new and Improved Automatic Insulator, of which the following is a full, clear, and exact description.

This invention relates to automatic insulators and closers for electric circuits.

It is intended to be used especially in connection with line-wires carrying electric currents; and the object of the invention is to provide improved means for automatically cutting out the broken end of a tightly-strung conductor, such as a line-wire.

A further object of the invention has been to provide a circuit arrangement whereby the flow of current in its circuit may be uninterrupted although the circuit has been severed at any point.

Further objects of the invention will appear more fully hereinafter.

Reference is to be had to the accompanying drawings, forming a part of this specification, in which similar characters of reference indicate corresponding parts in all the figures.

Figure 1 is a central section taken through one of my insulators and circuit-closers. Fig. 2 represents a portion of an electric circuit including several of my insulators and circuit-closers and illustrating the manner in which a circuit may be kept intact, although it is suddenly broken at some point. Like Fig. 1, the insulators or circuit-closers are shown in central section. Fig. 3 is a diagrammatic view showing a portion of two circuits. In this view the going and returning wires are both shown.

Referring more particularly to the parts, 1 and 2 represent wires which extend oppositely from an insulator or circuit-closer 3, and it should be understood that these wires 45 1 and 2 are, as usual, strung upon poles or similar supports and are subjected to considerable tension. This tension of course exerts two forces tending to pull the insulator 3 in opposite directions, though they 50 normally equalize each other, as will be readily understood, so that the insulator remains in equilibrium.

The body 4 of the insulator or circuit-closer is of substantially cylindrical form,

provided on its outer side with a longitudinally-disposed duct 5 for a purpose which will appear more fully hereinafter. This insulator is hollow within and provided, preferably, with a transversely-disposed diaphragm or head 6, centrally disposed, as indicated. The ends of the insulator are closed by removable plugs 7, which may be attached by screw-threads, as indicated. These plugs 7 have hollow cylindrical bodies 8, which project into the interior of the insulator, 55 but are of less diameter than the interior thereof, so as to present annular spaces 9 therebetween, as shown. Through the base of each plug an opening 10 is formed, and through these openings the wires 1 and 2, respectively, 60 pass, as shown. At the outer extremities of the bores 11, which are formed in the tubular bodies of the plugs 7, the extremities of the conductor 12 are received, the body of the said conductor being disposed in the aforesaid conduit or duct 5. Within the bores 11 plungers 13 are arranged, and these plungers are preferably formed with enlarged heads 14, the diameters of these heads being substantially the same as the interior diameter 70 of the body 4. The extremities of the wires 1 and 2 are attached to contact-plates 15, which are normally held in contact with the conductor 12, so that circuit is normally closed between the wires 1 and 2 through the 75 conductor, as will be readily understood.

In the annular spaces 9 aforesaid helical springs 16 are placed, as shown, and these springs thrust against the plugs 7 and against the heads 14 of the plungers 13. These 80 springs are, however, not of sufficient strength to overbalance the tension in the wires, so that they are normally held in a compressed condition. If by accident either of the wires 1 or 2 becomes broken, it will be 85 suddenly relieved of its tension, and when this occurs the corresponding spring will operate to drive the plunger with which it is in contact against the head or wall 6. In this way the broken wire would be disconnected 90 at the insulator and circuit-closer from the rest of the circuit.

I provide a circuit arrangement whereby an electric circuit may be maintained substantially intact, although the same may 100 have become broken at some point. To effect this, I provide the devices 17 17, which are of the same general form as my insulator

3. They are connected in circuit with wires 19, 20, and 21, which constitute a part of a main circuit.

Referring more particularly to the details 5 of the devices 17, these are provided, like the device 3, with plugs 18, in which are mounted movable plungers 22 22^a, said plungers being normally held in their outer extreme positions by the tension in the wires, as 10 stated above. In connection with the plungers, as before, spiral springs 23 are employed, which normally tend to force the plungers toward the central portion of the insulator-body. The bodies of the insula- 15 tors 17 are provided with conductors 24, the extremities whereof lie adjacent to and normally close contact with contact-plates 25 25^a, carried at the outer extremities of the plungers 22^a, as indicated. Near the middle 20 portion of the insulators 17 the conductor 24 is provided with laterally-disposed broken branches or legs 26 26^a. When the plugs 22 occupy their abnormal or innermost extreme 25 position, contact-plates 27, which they carry at their inner extremities, are adapted to engage with these legs 26, so as to close the circuit therethrough in a manner which will appear more fully hereinafter. It should be understood that when the contacts 27 are removed from the legs 26 the metallic 30 continuity through the legs is broken, so that they cannot transmit a current.

Parallel with the main circuit 28, which comprises the wires 19, 20, and 21, I arrange 35 an auxiliary or reserve circuit 29, which comprises wires 30, 31, and 32. These wires are connected by insulators or circuit-makers 33. As indicated, the construction of these devices 33 is substantially the same as that of the insulator 3, described above, with this exception, instead of a single conductor 12, such as used in the insulator 3, I provide two 40 separate conductors 34 and 35. These are arranged, as shown, so that they come to the outer surface of the insulator-body at substantially the middle portion thereof and afford means at the extremities of the insulator for closing a circuit through contact-plates 36, carried upon the extremities of the plungers 37. With this arrangement there is no 45 continuous metallic connection existing directly between the conductors 34 and 35. However, a continuous metallic connection may be made between these conductors 50 through the medium of wires 38 38^a, which connect them, respectively, with the legs 26 26^a aforesaid, belonging to the conductors 24 of the devices 17.

It should be understood that when the circuit 55 is intact under normal conditions the plungers 22^a, which occupy the adjacent extremities of the insulators 17, will hold their contact-plates 25^a against the corresponding extremities of the conductors 24, and with 60 this arrangement evidently the wires 19, 20,

and 21 will be connected directly through the conductors 24, so that they constitute a portion of a continuous metallic circuit. If by any accident the wire 20 should become severed, the plungers 22^a will be actuated by 70 their springs, so as to move into the position in which they are represented in Fig. 2. When this occurs, a circuit will be closed through the legs 26^a and through the wires 38^a, conductors 35, and through the wire 31. 75 Thus it will be seen that immediately upon the opening of the circuit between the devices 17 an auxiliary circuit is automatically substituted around the break. It will of course be understood also that while the main 80 circuit 28 is intact the auxiliary circuit 29 is inactive and passes no current. In practice with such an arrangement as this the main circuit will not be thrown completely out of use, and in case the circuit should be 85 an electric-light circuit total darkness would not follow upon the break. However, there would of course be for an instant a cessation of the current, which would constitute a signal, indicating that the circuit had been 90 broken at some point.

In Fig. 3, 39 indicates the outgoing main circuit-wire, while 40 indicates the incoming main circuit-wire. Parallel with these the auxiliary circuit-wires 41 and 42 are installed, 95 and these are connected at regular intervals by my insulators and circuit-closers 43. In practice it is desirable not to arrange the main circuit and auxiliary circuit upon the same supports or cross-trees. Hence the breaking 100 of the main circuit would not necessarily include a break in the auxiliary or reserve circuit.

Having thus described my invention, I claim as new and desire to secure by Letters 105 Patent—

1. In a device of the class described, in combination, an insulating-body of substantially cylindrical form, removable plugs seated in the extremities of said body, plungers 110 slidably mounted in said plugs said body having a longitudinally-disposed duct formed in the wall thereof and a conductor disposed in said duct and having laterally-disposed legs passing into said plugs, contact-plates 115 carried by said plungers and engaging said legs, springs pressing said plungers and line-wires attached to said contact-plates.

2. In a device of the class described, in combination, an insulating-body, a conductor having legs with breaks therein and mounted within said body, movable plungers mounted within said body, contact-plates carried thereby which may bridge said breaks, springs constraining said plungers in 120 the direction of said legs, and other contact-plates carried by said plungers and engaging said conductor at other points.

3. In a device of the class described, in combination, an insulating-body, a conduc- 125

tor disposed longitudinally in said body and having its extremities disposed in the extremities of said body, said conductor having laterally-disposed legs at substantially the middle portion of said body, said legs having breaks, movable plungers mounted in said body, springs constraining said plungers in the direction of said legs, contact plates carried by said plungers and which may bridge said breaks, and other contact-

plates carried at the opposite extremities of said plungers and engaging the extremities of said conductor.

In testimony whereof I have signed my name to this specification in the presence of ¹⁵ two subscribing witnesses.

GAËTAN M. CORELL.
